DESIGN FOR A DRESS

Jack Stolkin, New York, N. Y.

Application July 24, 1941, Serial No. 102,411

Term of patent 3½ years

To all whom it may concern:

Be it known that I, Jack Stolkin, a citizen of the United States and a resident of the city of New York, in the county of Bronx and State of New York, have invented a new, original, and ornamental Design for a Dress, of which the following is a specification, reference being had to the accompanying drawing forming a part thereof.

Fig. 1 is a front view of a dress showing my new design.

Fig. 2 is a rear view of the dress shown in Fig. 1.

I claim:

The ornamental design for a dress, substantially as shown.

JACK STOLKIN.
